UNITED STATES PATENT OFFICE

HENRY JAMES DOUGLASS, CHARLES D. DOUGLASS, AND MARCUS S. LEVE, OF SAN FRANCISCO, CALIFORNIA, ASSIGNORS TO PACIFIC CAN COMPANY, OF SAN FRANCISCO, CALIFORNIA, A CORPORATION OF NEVADA

MULTIPLE SPINDLE VACUUM DOUBLE SEAMER

Application filed October 19, 1931. Serial No. 569,758.

Our invention relates to improvements in double seamers, for uniting can ends to can bodies, and in particular reference to continuously operating multiple spindle double seamers, in which the closing operation is performed in a vacuum; and one of the objects of the invention is to engage the cans, as they are delivered to the machine at a slow rate of speed and gradually accelerate said speed, until they are traveling at the high speed of the seaming rollers, thus eliminating the spilling of the contents of the cans.

Another object of the invention is to receive the cans in the machine at a definite elevation, and carry them at this constant elevation through the machine, until the double seaming is completed, and the cans are discharged, thus avoiding the spilling of the contents of the cans by a rapid vertical movement.

Another object is to enclose the can together with the seaming rollers, the timing cam, and the gearing, operating said timing cam, into a hermetically sealed chamber, create a vacuum inside the chamber, and unite the can end with the can body, while the vacuum remains in the chamber.

Another object is to provide marking mechanism for stamping each can-end, after it has left the can-end stack and before it has been placed on top of the can body.

Another object is to carry the can ends for some distance in alignment with, and at some space above the can bodies, and gradually lower the can-ends upon the can bodies, in order to lower slowly any fruit, which may float upon the liquid in the can, and avoid the spilling of the liquid.

Another object is to provide automatic means for preventing the feed of a can-end, in case there is no can body delivered to the machine to receive said can-end.

Another object is to provide automatic means for stopping the machine, if a can body has been delivered, and no can-end has been supplied.

Another object is to provide automatic means for keeping the machine running and for preventing the delivery of a can-end, if no can body has been supplied to the machine.

Another object is to prevent the creating of a vacuum inside a vacuum casing, if no can has been placed inside said casing.

With these objects in view, the machine is provided with a circular rotatory disc, upon which the filled can bodies are placed in comparatively close formation and are carried around with a slow speed and resting upon said circular disc, until they become engaged by accelerating devices, which are moving at first with the same slow speed, and then gradually increase the speed of the cans, until they obtain the full speed of the seaming spindles carried upon a seaming turret.

The machine is also provided with a stationary can-end magazine, carrying a stack of can-ends and furnished with automatic feeding mechanism, which is controlled by the can bodies, as they are delivered upon the rotary disc and are adapted to separate the lowermost can-end in the stack and introduce it in a guiding groove of a can-end track, and bring it opposite a marking device, where the can-end remains at rest, until after it has been stamped.

From the marking devices the can-ends are carried without interruption along said track and are brought in vertical alignment with, and within a short distance above the top of the cans, where the said can-ends and the can bodies remain in alignment, both moving with the same accelerating speed, until they are brought opposite the seaming spindles of the turret, and during their travel towards said spindles, the can-ends are gradually lowered, pressing down slowly any floating fruit, which may project above the tops of the cans, without spilling any of the liquid.

The seaming turret comprises a number of discs, secured to a tubular vertical shaft and driven with a continuous uniform motion.

A number of platforms are supported by the lower disc of the turret; said platforms receive the cans delivered by the accelerating devices and support them, while being carried around during the double seaming.

The upper discs of the turret are provided with guides, within which are slidably

mounted vacuum casings carrying the seaming spindles; said casings being arranged in alignment with said platforms, and cylindrical shells are slidably fitted around the platforms.

When a can body and a can-end are placed upon a platform, a knockout rod immediately descends, engaging the can-end and holds it down upon the can during the operation of 10 double seaming.

The seaming spindle together with the outer casing are then lowered, until the seaming rollers are above the can at the elevation required for double seaming, and the cylindrical shell is raised upwards, until the upper edge comes in contact with the outer casing.

The can is then hermetically closed within the casing and the air is then removed by turning a valve for one quarter turn, connecting the interior of the casing with a tank, in which the air is kept at a high vacuum; the air inside the can becomes rarefied and in this rarefied condition the final closing of the seam is accomplished.

25 The interior of the casing is then disconnected from the vacuum tank and opened to the atmosphere, by giving the valve one quarter turn in the opposite direction, and the cylindrical shell is then lowered; the seaming spindle, together with the outer casing, is raised and the sealed can is removed by an extracting arm.

The following is a more complete description of the invention, which taken in connection with the accompanying drawings, 35 discloses a preferred embodiment thereof.

Referring to the drawings:

Figure 1 is a plan view of the machine.

Figure 2 is a front elevation.

40 Figure 3 is a vertical section, taken on line 3—3 of Fig. 1.

Figure 4 is a sectional plan, taken on line 4—4 of Fig. 3, showing the driving mechanism and the lower gearing of the machine.

45 Figure 5 is a sectional plan, taken on line 5—5 of Figure 3, showing the can body feeding mechanism and the accelerating mechanism.

50 Figure 6 is a plan view and Figure 7 is a sectional side elevation of the mechanism for raising or lowering the cylindrical shell for enclosing the can in a hermetically sealed chamber.

Figure 8 is a vertical section through the 55 center of one of the seaming spindles.

Figure 9 is a cross section of the seaming spindle, taken on line 9—9 of Figure 8.

Figure 10 is a cross section of the spindle, taken on line 10—10 of Figure 8.

60 Figure 11 is a cross section of the spindle, taken on line 11—11 of Figure 8.

Figure 12 is a vertical section of the vacuum casing of the seaming spindle, showing the seaming rollers, the timing cam, the inner side gearing operating the timing cam, and

the mechanism for forming a running air tight joint between the hub of the casing and the outer sleeve, whereby the seaming rollers inside the casing are actuated from the outside.

70 Figure 13 is a vertical section through the center of the upper part of the seaming spindle and the mechanism for raising and lowering the seaming spindles and for manipulating the knockout rod.

75 Figure 14 is a vertical section through the upper portion of the turret.

Figure 15 is a plan of a portion of the machine, illustrating the operation of the safety devices.

80 Figure 16 is a detail of the top of the knockout rod and of the sliding head.

Figures 17 and 18 are a side elevation and an end view respectively of the marking device.

85 Figure 19 is a plan view, partly in section, of one of the seaming levers.

Figure 20 is a side elevation, partly of section, of the same lever.

90 Figure 21 is a vertical section through the center of the turret.

95 Figure 22 is a plan of the lower disc of the turret with the mechanism for raising or lowering the cylindrical shell removed, in order to show clearly the manner of connecting and disconnecting the vacuum casings of the seaming spindles with a vacuum tank.

Figure 23 is a central vertical section through the vacuum chambers, port holes, and valves manipulating the production of 100 a vacuum in the traveling vacuum casings, by connecting them with a stationary pipe leading to a vacuum tank.

Figures 24 and 25 are cross sections 105 through the ports of the plug valves; Figure 24, showing the plug closing the port holes leading from the vacuum chamber and connecting the port leading from the vacuum casings of the spindles with the atmosphere; and Figure 25, showing the opening to the atmosphere closed and the port hole leading from the vacuum chamber to the vacuum casings of spindles open and Figure

110 26 is a sectional elevation of the can-end feed magazine, taken on line 26—26 of Figure 15, showing in detail the action of the can-end separating disc, and the can-end propelling pins.

115 The machine consists of the base 1 carrying the uprights or columns 2 and 3, to which some parts of the framework of the machine are secured.

At the bottom the base is provided with a flange 4, resting on the floor and with a horizontal ledge 5, to which a bottom plate 6 125 is secured by means of the bolts 7.

The top 8 of the base carries a plurality of bearings, in which are mounted some of the upright shafts of the machine; and the bottom plate 6 is similarly furnished with 130

bearings supporting the lower ends of said shafts.

The inside of the base is partially filled with oil and most of the gearing for driving the machine is placed within the base.

The top 8 of the base is provided with the bearing 9, fitted with the bushing 10, in which is mounted the lower end of the tubular shaft 11 of the rotatory turret, and inside the tubular shaft is placed the central shaft 12, resting at the lower end in the bearing 13, and at the top in the bearing 14, provided in the cylindrical casting 15. This casting 15 is adjustably secured to the horizontal top plate 16, which is fastened to the columns 2 and 3.

A thrust ball bearing 17 is placed above the bushing 10, to sustain the weight of the turret.

The tubular shaft 11 carries a circular lower disc 18, provided with a number of bosses 19, equally spaced one from the other. Each of said bosses is furnished with a bore, in which the reduced end of a vertical rod 20 is fitted and securely held by the nut 21.

The top of the rod 20 is reduced in diameter and carries the lower chuck casting 22, which is circular in plan, and which is secured to it by means of a screw 23.

The lower chuck castings are provided with a semi-circular vertical projection, forming the trueing jaws 24, adapted to embrace one half the circumference of the can body; and its object is to help form the can body into a circular shape and for aligning the can body with the seaming mechanism above.

A steel wearing plate 25 is secured to the top of the chuck casting 22.

The cans to be seamed are placed upon the lower chuck, and they remain at the same elevation, until they are seamed and discharged from the machine.

The chuck casting is surrounded by a cylindrical shell 26 fitted slidably to the outer surface of the chuck casting, and formed at the lower end with the screw thread 27, whereby it is secured to the outer rim 28 of the cylinder bottom plate 29, and made fast by the jam-nut ring 30.

The cylinder bottom plate 29 is formed with a central hub 31, bored to slide upon the vertical rod 20, and with radiating arms 32, connecting said hub with the outer rim.

Upon the hub 31 is fitted to slide a shifting block 33, which is held in place by a compression spring 34, engaging at one end the arms 32 and at the other end pressing against the top of said block, holding it yieldingly against the collar 35, which is secured to the lower end of said hub.

The object of the spring is to limit the force with which the cylindrical shell is pressed upwards and to compensate for any wear or irregularities in construction or adjustment which may vary the extent of travel of the block.

By moving the block 33 up or down, the cylindrical shell 26 is raised, when the vacuum chamber is to be closed, and lowered, when the vacuum chamber is to be opened.

The upper end of the outer rim 28 is reduced in diameter, forming a seat for a rubber packing ring 36, which ring forms an air tight joint with the bottom edge of the chuck casting 22, when the cylindrical shell is at the upper end of its stroke, as shown in Figures 7 and 21.

The top edge of the cylindrical shell 26 at the same time comes in contact with a rubber packing ring 37, which is fitted in a groove on the bottom cover 68 of the vacuum casing 65 of the seaming spindle, as it will be herein-after described.

The tubular shaft 11 carries, besides the circular lower disc 18, the lower guiding disc 55, for guiding and steadyng the cylindrical shells 26, together with the lower chucks 22 and with the cans, and the three discs 56, 57, and 58 which form the upper part of the turret, and in which the seaming spindles are mounted; the discs 55, 56, 57, are keyed to said shaft 11 and are provided with guides, arranged in vertical alignment with the lower chucks 22, while the disc 58 is mounted loosely upon the central shaft 12, and is secured to the flange 110 of the uprights 108, carried by the disc 57; the disc 56 is also secured to the disc 57 by the uprights 107 and the flanges 109.

The vertical guides 59 in the disc 55 consist of split bearings, formed with caps 60 and bored to fit the outside diameter of the cylindrical shells 26.

The vertical guides in the disc 56 comprise the pockets 62, cored in the discs 56, and having the guiding grooves 63 milled out to fit guide strips 64, provided on the outer casings 65 of the seaming spindles.

The double seaming mechanism, best shown in assembly in Figures 2, 3, and 21, and in detail in Figures 8, 9, 10, 11, and 12, consists of a cylindrical casing 65, formed at the two ends with the flanges 66 and 67. A bottom cover 68 is secured to the flange 66 and a hub casting 69 is secured to the flange 67.

The hub casting is formed of a flat circular plate 70, upon which is cast a cylindrical housing 71, forming a nest for a pair of gears 72 and 73. A hub 74 extends above said housing and a pocket 75 runs from said housing to the edge of the circular plate, where it is closed by a cover 76.

A multitubular shaft passes through the hub 74 and upon said shaft are assembled the several devices forming the double seaming mechanism. This shaft consists of a rotatable outer sleeve 77, and of the non-rotatable inner tube 78, which carries at the lower end the upper chuck 159, engaging the can-end and sustaining the pressure of the seaming 130

rollers upon the seam, and of the non-rotatable knockout rod 79.

A spur gear 111 is keyed to the upper part of the sleeve above the hub casting and is driven with a high rate of speed from a spur gear 112, shown in Figures 2, 3, and 21, keyed to the central shaft 12 of the machine.

For manipulating the action of the seaming rollers inside the vacuum casing from the outside, a spur driving gear 72 is keyed to the sleeve just below the hub 74, and below said driving gear is fitted to turn loosely a gear 73, furnished with a long hub 80, upon which is keyed a timing cam 81. Within the pocket 75, there is secured a stationary pin 82, upon which is mounted to turn a pinion 83, meshing with the driving gear 72, receiving motion from it and carrying keyed to its hub 84 a pinion 85, adapted to engage the gear 73, and thus impart motion to it and to the timing cam 81 carried upon its hub.

The ratio of the gearing between the driving gear 72 and its meshing pinion 83, and between the gear 73 and its meshing pinion 85, is slightly different, so as to cause the timing cam 81 to run either slightly ahead of the sleeve 77, or slightly behind said sleeve, so as to gain or lose one half of a revolution during a cycle of operation of the seaming mechanism or during one complete revolution of the turret.

Below the timing cam 81, the seaming head 86 is keyed to the sleeve 77 and is clamped by the nut 104.

35 This seaming head 86 is circular in shape and is made of such a diameter, as to fill up the space inside the outer casing, thus reducing the volume of air to be removed, in order to obtain the required degree of 40 vacuum.

The seaming head (see Figures 8, 9, 10, and 11) has a continuous rotary motion and is provided with two bearings 87, oppositely disposed, and furnished with the bushing 88, 45 in which are mounted shafts 89.

At the lower ends the short shafts 89 have keyed to them the seaming levers 94, which are formed with a central hub 95, and with sockets 96 at each end.

50 Within the sockets are fitted the eccentric bushings 97, shown in Figures 19 and 20. These bushings are cylindrical in shape and are furnished with threaded holes drilled out of center, into which sleeves 98 are fitted.

55 At the lower end of the sleeves 98 the inner races 99 of roller bearings are shrunk on, while the outer races of said bearings are formed in the interior bore 100 of the seaming rollers 101 and 101a.

60 The rollers 101 are carried at one end of the seaming levers 94 and they perform the first operation of the double seaming, while the rollers 101a are carried upon the other end of the seaming levers and perform the 65 second operation of the double seaming.

The height of the seaming rollers may be adjusted, by raising or lowering the sleeves 98 within the bushings 97, and clamping them by the jam nuts 102, while the distance of the seaming rollers from the center of the can may be adjusted, by turning the eccentric bushings 97 within the sockets 96 and clamping them in place by screws 103.

Upon the upper ends of the short shafts 89 are keyed the cam arms 90, provided upon 75 their free ends with the pins 91, carrying the cam rollers 92, which are working in the groove 93 of the timing cam 81.

The groove 93 of the timing cam is of a symmetrical shape; each half of said groove 80 is arranged to engage a cam roller 92 of the operating arms 90 and thus act upon the seam at two opposite points simultaneously, counterbalancing the side pressure upon the 85 chuck.

The shape of the cam groove 93 is such, as to keep the seaming rollers 101 and 101a, which are revolving continuously, at the neutral position or equally distant from the center of the can, at the time they are lowered 90 for action, and immediately start feeding the first set of rollers 101, carried at one end of the seaming levers 94, towards the center of the can, until a seam is formed, by curling the flange of the can body and the outer edge 95 of the can end in the usual way, and then the operating arms 90 are swung in the opposite direction, applying the second set of rollers 101a, carried upon the other end of the seaming lever 94, to the seam, flattening it 100 out and making it air tight.

Within the hub 74 of the vacuum casing, any kind of a stuffing box may be arranged, to prevent the inflow of air into the casing between the rapidly rotating outer sleeve 74 105 and the stationary bearing, but a preferable construction is here illustrated.

The inside of the hub 74 is fitted with a ball bearing consisting of the outer ball race 113, held tight in the hub 74 and of the inner race 114, which is secured to the sleeve 77. Beneath the ball race 113 is placed a ring 115, having a plurality of concentric grooves 116 formed on its upper face and closely spaced, forming a number of concentric ridges between them.

This grooved ring rests upon a shoulder formed in the inner bore of the hub 74 and in turn supports the ball race 113, which is held down firmly by the nut 117.

Co-operating with the ring 115 is another ring 118, which is resting upon a shoulder on the sleeve 77 and is provided on its lower face with a number of concentric grooves and ridges, arranged so as to intermesh with those of the ring 115. Above said ring 118 is placed the inner ball race 114 and both are clamped to the sleeve by means of an oil cup 119, which is provided with a screw 120

thread fitting in corresponding threads on the sleeve 77.

At the upper end of the hub 74 a screw thread is cut and a flanged casting 121, formed with a raised rim 122, is secured and clamped by the jam nut 123 and a circular diaphragm plate 120 is placed upon the rim and clamped there by the nut 124.

The diaphragm plate 120 is provided with a central opening, through which a cylindrical tube piece 125 passes and is secured to it by the nut 126.

The bottom of the tube piece 125 is smoothly ground to fit the bottom of the oil cup, which is partially filled with oil and seals the running joint between the rotating sleeve 77 and the stationary bearing.

The vacuum inside the casing produces a low pressure beneath the diaphragm plate 120 and the atmospheric pressure upon the upper face of the diaphragm keeps the lower end of the tube 125 in contact with the bottom of the oil cup 119.

The grooved rings 115 and 118 form a loose running fit, and their object is to retard the speed of inflowing air, (if any had entered between the top bore of the stationary tube 125 and the outside of the rotating sleeve 77, and from there leaked through the running joint at the bottom of the tube 125) by causing said inflowing air to perform a great number of reversals before it could enter into the vacuum chamber.

Above the diaphragm mechanism the sleeve 77 is provided with the gear 111, and extending above said gear for some distance terminates within the bore of a sliding head 127, whereby the seaming spindle is raised and lowered during the operation of the machine, and where anti-friction ball bearings are placed, permitting the rapid rotation of the sleeve 77 within the bore of the non-rotatable sliding head 127.

For keeping the joint between the rotating outer sleeve 77 and the stationary inner tube 78 air tight, the following construction is provided:

The lower part of the sliding head 127 is bored to fit loosely on the top part of the sleeve 77, and it is then counterbored at 128, to form a seat for the felt washer 129; and above said counterbore the diameter is again enlarged, forming a shoulder 130. A grooved ring 131, similar to the ring 115 above described, is fitted within the bore, resting upon the shoulder 130, and in turn supporting the outer ball race 132 of a ball bearing, held firm in place by the sleeve casting 133.

At the top the inner bore of the sleeve 77 is counterbored and threaded at 134, to receive the lower end of the shank of a steel oil cup 135.

The inner race 136 of the ball bearing is then placed upon the shank next to the bot-

tom of the oil cup, followed by another grooved ring 137 cooperating with the ring 131, and the shank is made fast within the end of the sleeve 77.

The sleeve casting 133 is furnished with a cover 151, secured to it by the screw threads 150.

Within the inside bore of the sleeve 77 is fitted the inner tube 78, which is provided at the top with a screw thread passing through the threaded sleeve casing cover 151, where it is made tight by the jam nut 152 and, extending upwards, it receives the guide 153 of the knockout rod 79.

Within the cup 135 is placed a diaphragm mechanism, comprising a steel circular plate 154 provided with a central opening fitting the outside of the tube 78 and clamped to it by the jam nuts 155 and 156.

At the outer periphery the plate 154 is clamped within the counterbore in a ring 157 by means of the threaded ring 158.

The ring 157 has the lower face fitted closely to the bottom of the oil cup 135, which is partly filled with lubricating oil.

At the bottom the inner tube carries the upper chuck 159, against which the can ends are pressed by the seaming rolls during the seaming operation. This chuck can be adjusted vertically in relation to the seaming rollers by the screw threads at the bottom of the inner tubing and made fast by the jam nut 338.

Within the inner tube 78 is placed the knockout rod 79, carrying at its lower end the tip 160.

The knockout rod 79 extends upwards through the inner tube and at the upper end it is reduced in diameter, forming a shoulder 161.

The reduced end passes through the rod guide 153 and the shoulder 161 closes the opening at the upper end of the tube air tight, when the cylindrical casing 65 together with the seaming rolls is in the downward position.

From the above description of the gearing inside the cylindrical casing 65, it may be noted, that the set of meshing gears 72 and 83, and the set of meshing gears 73 and 85 are mounted to turn around the same vertical centers, and therefore the distance between the centers of one set has to equal the distance between the other set; it may also be noted, that the ratio of gearing of the one set of gears is slightly different than the ratio of the other, so as to cause the timing cam 81 to run either slightly ahead of the sleeve 77, or slightly behind said sleeve, so as to gain or lose one half of a revolution during one complete revolution of the rotatory turret.

When the number of teeth in each of the gears has been figured, which produce the slightly different ratios in the two sets, it will in most cases be found, that the sum of

the teeth of the one set is slightly different than the sum of the teeth of the other set, requiring a slightly different distance between the centers of the two sets, if the pitch of the teeth in the two sets are alike.

In order to equalize the distance between the two sets, the pitch of the teeth of one set will have to be slightly different than in the other.

10 By using a standard gear cutter for producing one set of gears, it will be found that there is no standard gear cutter on the market to produce the other set, and a special gear cutter with an odd pitch will have to be made.

A set of gears with an odd pitch are therefore not desirable in a machine of this character, since they cannot be readily replaced.

15 In order to overcome the above difficulty, 20 the set of gears requiring the greater distance between centers are cut in the ordinary way, while the gears of the other set are cut by the same standard cutter, but the teeth, instead of running parallel to the shaft, are 25 cut at a slight angle to said parallel line, as shown in Figure 12.

20 The mounting of the seaming spindles upon the turret is best shown in Figures 2, 3, 13, and 21; said mounting is accomplished by 30 placing the cylindrical casings 65 within the pockets 62 on the guiding disc 56, placing the guide strips 64 within the grooves 63, and placing the hub 74 within the split guides 105 furnished with the cap 106, while the sliding 35 head 127 is placed within the guide 140 on the guiding disc 58, with the arms 138 entering the slots 352.

35 The sliding head 127 is thus free to move up or down, but is prevented from rotation 40 by the arms 138.

40 For imparting vertical motion to the sliding head 127, there are provided flanges 141 at the top of the guides 140, and upon said flanges are secured the brackets 142, each 45 bracket being furnished with a forked bell crank lever 143, pivoted at 144, and carrying a cam roller 145, working in a circular cam track 146, secured to the stationary cylindrical casting 15. The rotation of the turret 50 around the central shaft of the machine carries the cam roller 145 along the groove of the cam track, and causes the swinging of the bell crank levers upon their pivots 144.

55 Cam plates 147 are secured to the arms of the forked lever, and are furnished with the cam grooves 148 engaging cam rollers 149, carried by the arms 138 of the sliding heads 127.

60 The swinging of the cam plates 147 causes the rollers 149 to follow the cam grooves 148 and to raise or lower, and thus raise or lower the sliding heads 127 together with the seaming spindles and with the vacuum casings 65.

65 Each of the brackets 142 is provided with

an arm 162, furnished with the bearings 163 for a rocking shaft 164.

The shaft 164 carries a segment of a gear 165, meshing with the teeth of a rack 166, provided on the sliding block 167, which is 70 fitted to slide in the knockout rod guide 158 and is secured to the reduced upper end of the knockout rod.

An arm 168 is keyed to the shaft 164, carrying at the free end a cam roller 169, engaging a circular cam track 170, which is secured to the circular cam track 146 by means of the brackets 171.

The rotation of the turret around the central shaft of the machine carries the cam 80 roller 169 along the groove of the cam track 170, imparting a swinging motion to the arm 168 and to the gear segment 165, raising or lowering the rack 166 and the knockout rod 85.

The cam tracks 146 and 170 are so shaped, as to cause the seaming spindles and the knockout rods to ascend and to descend once for each revolution of the turret, and a cam track 54, which will now be described, causes the raising or lowering of the cylindrical casings 26, which in cooperation with the vacuum casings 65 of the seaming spindles 90 form a hermetically sealed chamber, within which the cans are enclosed during the seaming operation.

The means actuating the shifting block 33 consists of a bracket 38, secured on the top of the lower circular disc 18, and being provided with a boss 39, in which is secured a fulcrum pin 40. A rocking lever 41, shown in plan in Figure 6, and in elevation in Figure 7, bifurcated at one end, where it carries the bearings 42, is mounted upon the fulcrum pin 40, and at the other bifurcated end, where it carries the pivoting pins 43, it straddles the shifting block 33 and engages by means of the pins 43 the wearing blocks 44, which are adapted to slide inside slots in said block 33.

100 The raising or lowering of the lever 41 raises or lowers the cylindrical shell 26.

The rocking lever 41 is slotted in the middle and within the slot a cam lever 45 is fitted.

105 The said cam lever is secured on a shaft 46, working in a bearing 47, and it has at the free end a cam slot 48, in which a cam roller 49 is fitted. This cam roller 49 is carried by a pin 50, secured in the two lugs 51 at the middle of the lever 41.

An arm 52, secured at the end of the shaft 46, carries at the free end a cam roller 53, fitted to work in a circular cam track 54, which is fastened to the top 8 of the base.

110 The rotation of the turret around the central shaft carries the roller 53 along said track 54, and the raising or lowering of said roller by the track raises or lowers the rocking lever 41, whereby the cylindrical shell 26 is raised or lowered.

The cam slot 48, it may be observed, is so shaped, as to have the extreme right end portion of it concentric with the center of the shaft 46, as shown at 48a in Figure 7, while 5 the rest of the slot forms a considerable angle with a concentric circle, the result is, that when the rocking lever 41 is in the upward position keeping the vacuum chamber closed, the roller 49 is engaged by the concentric 10 portion 48a of the cam slot. Any small irregularities of the cam track 54, which produce slight movement of the cam lever 45 do not affect the rocking lever 41, and any pressure upon the free end of the rocking 15 lever 41 is transmitted to the lever 45 by the roller 49 in the direction of the center of the shaft 46, there being no tendency to swing said lever one way or another, or to produce pressure by the roller 53 upon the cam track 20 54 to cause wear upon said track.

The can bodies are received upon the rotating disc 173 from any source of supply (not shown) and are guided by the guide rail 174. Above the disc 173 is placed the star member 25 175, which determines the timing of the cans to harmonize with the seaming turret.

The disc 173 is secured to a circular plate 172 furnished with a hub 197, keyed near the 30 top of the vertical shaft 176, which is mounted at the bottom in the bearing 177 on the bottom plate 6 of the base and at the top in the bearing 178 on the platform 179.

Adjacent the can receiving disc 173 is placed the can accelerating mechanism, which 35 receives the cans at the disc, where they travel in comparatively close formation and therefore with a slow speed and deliver them to the seaming mechanism on the turret, where they are spaced farther apart and 40 therefore travel at a greater rate of speed.

The accelerating mechanism comprises a vertical shaft 180, mounted at the bottom in the bearing 181 on the bottom plate 6 of the base, and near the top in the bearing 182 45 carried by the cam track casting 196, which is secured to the platform 179.

At the top the shaft 180 carries the bar guiding head, consisting of the lower guiding plate 183, formed with the guiding groove 50 184, and having a hub 185, whereby it is keyed to the shaft 180; and of the top plate 186 provided with guiding groove 187. The plates 183 and 186 are fastened together by the screws 188 in such a manner, as to have 55 the two grooves 184 and 187 set at right angles to one another.

Sliding bars 189 and 190 are fitted in the grooves 184 and 187 respectively, and they carry at the ends the trueing jaws 191. The 60 bars are thus located at different elevations, the bar 189 being below the bar 190.

Cam roller pins 192 are secured near each end of the sliding bar 189, and pins 193 are similarly secured near the end of the bar 65 190 and cam rollers 194 are mounted upon

said pins. The pins 193 are longer than the pins 192 and are formed with a spacing shoulder 195, shown in Figure 3, in order to bring the cam rollers of the two bars to the same level.

70 A cam track 196 is secured to the platform 179 below the sliding bars, said cam track being of a symmetrical figure and placed on the table in such a manner, as to have the axis of the symmetrical figure coincide with the line joining the centers of the accelerating shaft 180 and of the turret shaft 12.

The cam track 196 engages the cam rollers 194, and during the rotation of the accelerator shaft, causes the sliding bars 189 and 190 to slide within the guides 184 and 187, moving at one time the trueing jaws 191 nearer the center of the shaft 180, when said jaws first receive a can body from the rotary disc 173, and farther away from said shaft as the can is being moved towards the seaming turret. The rate of speed of said trueing jaws will increase, as their distance from the center of the shaft 180 increases, and when the jaws are near the line of the axis of the cam track, they will run with the same rate of speed as the seaming spindles of the turret.

The cam track is so formed at 337 near said axis, as to cause the said trueing jaws to travel for a short distance along the path of the seaming spindles and in alignment with them, and during said travel the trueing jaws 191 of the sliding bars and the trueing jaws 24 of the lower chucks engage the can body all around, giving it a perfect cylindrical 95 shape and the can-end is during this time placed upon the can body and the knockout rod 79 is brought down to engage the can-end, and holding it down, prevents its rotation during the operation of the double seaming.

The cans traveling from the rotary disc 173 to the turret are guided by the rails 198 and 199 and are propelled forwards by the trueing jaws 191.

The cam track 196 engages one cam roller during a half of a revolution of the shaft 180, and just as one of the rollers on a sliding bar leaves the cam track, the other enters and in this way there is no interference to the motion of the two rollers, if there are slight irregularities in the track.

The top 8 of the base is formed with an opening 200 and above said opening is erected the platform 179, which is supported from 110 said base by the flanged plates 201 and by the columns 2 and 3.

The top of the platform carries a number of vertical ribs 202, which are formed at the top with the surfaces 203 and 204. Upon the lower surface 203 is secured a smooth steel plate 205, upon which the cans rest, while being propelled by the trueing jaws 191, and upon the upper surface 204 is placed the lower guiding rail 199 and above said guiding rail 120 125 130

a spacing casting 206, both being secured to the upper surface by the cap screws 207.

Upon the upper surface of the spacing casting 206 is secured the upper guiding rail 198.

5 The automatic can-end feed mechanism of the following description is secured to the spacing casting 206:

At an elevation above the top of the can bodies there is secured the can-end feed mechanism, which consists of a circular flange 208, forming the base of a can-end magazine, and of a grooved can-end track 209 projecting at one side of said flange, and carried at an elevation above the tops of the cans and brought 10 to a point, where the can bodies are first engaged by trueing jaws 191, and thence it is carried along the path of travel of said jaws, terminating just beyond the central line of the symmetrical cam track 196.

15 The circular flange 208 has a bore 210 just slightly larger than the outside diameter of the can-ends, and above the upper surface are erected a number of guide rods 211, which are placed so as to steady a stack of can ends and 20 guide them into the bore 210.

25 At one side of the flange 208 there is milled out a slot 212, within which is fitted a plate 213, the inner end of which projects a short distance inside the bore 210, thus giving support to one side of the stack of can ends.

30 Adjacent the flange 208 is located the can-end separating and feeding member, which consists of a vertical shaft 214, mounted in the lower bearing 215, provided on the bottom plate 6 of the base; and at the top in the bearing 216, carried by the platform 179.

35 The shaft 214 carries near the top the can-end separating disc 217, to the upper surface of which are secured the two can-end separating plates 218.

40 The disc 217 is best shown in plan in Figure 15. It is of a diamond shape, with the obtuse angles cut away along circular arcs 219, concentric with the center of the shaft 214, said arcs running along for some distance and terminating abruptly at 220, where notches are cut away, forming the gauging 45 supporting tongues 221.

45 At the oblique angles the ends are rounded up, and the can-end propelling pins 227 are fastened, being at the top flush with the upper surface of the disc, and, extending downwards, project for some distance below the lower surface of the disc.

50 The separating plates 218 have a thickness of a can-end, and their outlines on the outside consist of the circular concentric arcs 222 and 223 joined by the arc 224; they are both alike, being semi-circular, and are secured 55 to the upper surface of the disc 217 in the manner shown in Figure 15, their abutting edges at the joints running radially, and the forward end of one plate extending beyond the rear end of the other, exposing the projecting portions 225, which are bevelled off 60

on the lower surface, forming knife edges. The knife edges enter between the lowermost can-end of the stack resting upon the gauging tongue 221 and the can-end next above it, separating them, and forcing one side of the lowermost can-end down, bringing it to rest upon the shelf 226.

65 In practice the stack of can-ends is supported at one side by the plate 213, and at the other side by the end 267 of a steel strip 266, carried upon one arm of a bell crank lever 262.

70 When a can arrives at the point 268, it engages the feeler arm 256, causing it to swing outwards, thus actuating the bell crank lever 262 by means of the rod 264, withdrawing the point 267 of the steel strip 266 from beneath the can-end stack, and letting it rest upon the edge of the separating plate bounded by the 75 arc 222 which extends within the bore 210 of the magazine.

80 When the disc 217 in its motion brings the arc 223 opposite the stack, the latter drops down upon the gauging tongue 221, which determines the height of the dividing line 85 between the lowermost can-end and the one next above it, and at which elevation the knife edge of the projecting portion 225 of the separating plate is located. This knife edge comes between the lowermost can-end 90 and the one above it, moves the former down and gives support for a while to the can-end stack, until the can at 268 moves away, permitting the feeler arm 256 to return to its original position by the spring actuated rod 264, thus returning the point 267 of the steel strip under the stack to support it.

95 The can-end separated by the point 225 remains resting at the farther end upon the plate 213, while the other end is forced down and remains resting upon the shelf 226 below, and in this inclined position it remains, until one of the propelling pins 227 engages it, and moving it forward, carries it off the 100 plate 213 and directing it into the groove 228 of the can-end track 209, delivers it to the marking mechanism.

105 The marking mechanism, shown in detail in Figures 17 and 18, comprises the frame 229, formed with the vertical guide 230, in which is mounted the shank 231 of the upper type holder 232. This type holder is furnished with a T slot 233, in which the type is inserted and made tight by means of the wedge 234, having the end turned and screw threaded and provided with a jam nut.

110 Below the guide 230 there is provided an arm 235, formed with a T slot 233, in which the lower type is secured by a similar wedge 234.

115 The top of the shank 231 is threaded, and to it is secured a head piece 236, furnished with a slot in which the short arm of the operating lever 237 is fitted. This lever is fulcrumed on a pin 238 secured upon the up- 120

right 239 on the frame, and the other end of the lever connects by means of the pin 240 with an upright rod 241, mounted in a guide 242 provided on an arm 243 of the frame. A 5 spring 244 keeps the short arm of the operating lever 237 and the upper type in the upward position.

The frame 229 is clamped to a base 245 by means of the clamping jaw 246, which engages the flange 247 of the frame 229, and clamps it tight, when the screw 248 is tightened. The base 245 is secured to the platform 179 in such a way, as to bring the type of the marker near the center of the can ends, 10 and the top of the lower type to be on the level of the bottom of the can-end.

A portion of the can end track 209 is cut away at 249 to permit the entrance of the arm 235.

20 The means for actuating the operating lever 237 consists of a cam 250, secured upon the shaft 214, engaging a cam roller 251, carried upon the end of a swinging arm 252, loosely mounted upon the end of an upright 25 shaft 253.

The swinging arm is provided on its upper face with a rib 254, running across it, the upper surface of said rib being formed into a cam, engaging a roller 255, carried upon 20 the lower end of the upright rod 241, imparting to it an up and down motion, and thus bringing down the upper type of the marker upon the can-end, each time the cam 250 has made one half of a revolution, or each 25 time a can-end has been delivered to the marker.

The can end remains at the marker, until one of the trueing jaws 191 carried upon the sliding accelerating bars 190 approaches, 10 and, engaging it by means of the upwardly projecting pin 380, carries it through the entire length of the track 209.

The can end track is so shaped, as to move the can ends from the marker along a path, 15 the center line of which deviates but slightly from the path of travel of the pins 380, until they are brought to the point where the trueing jaws 191 first engage the can bodies, and thence to carry them in alignment with 20 said jaws, until they pass for a short distance beyond the center line of the cam track 196 below, where the cam rollers 192 and 193, traveling along the portion 337, cause the trueing jaws to move in alignment with the seaming spindles, when the knockout rod 79 is lowered upon the can end to hold it down upon the can body.

The can end track 209 is secured above the spacing casting 206 at a slight angle, the side 20 at the discharge end being about one inch lower than the opposite side, in order to lower the can ends upon the can bodies gradually, thus lowering slowly any fruit, which may float above the surface of the liquid in the 35 can, without spilling the liquid.

The machine is provided with certain safety devices, which will now be described:

In practice the following conditions regarding the delivery of cans and can-ends may occur.

1. A can may have been delivered and a can-end has been delivered; this is the condition when the machine is normally working. The safety devices have to keep the clutch on the driving shaft thrown in, so as to supply 75 the power to run the machine.

2. There may have been no can delivered to the machine, nor a can-end thereto, which may happen by a coincidence, or when it is desired to run the machine empty in adjusting it. In this case also the clutch is to be thrown in supplying power.

3. There may be a can delivered, but no can-end, which is the case, when the stack of can-ends were all used up, and the operator has failed to supply the same, or for any other reason. In this case, the safety devices have to thrown out the clutch on the driving shaft and stop the machine.

4. There may be no can delivered to the machine, while there are can-ends in the stack. In this case the automatic safety devices have to arrest the delivery of a can-end.

The safety devices herein to be described 95 fulfill all the above requirements, as will appear from the following description:

On the frame of the machine are pivoted the feeler arms 256, 257, and 258.

The arms 256 and 257 are pivoted on the 100 pivots 259 and 260 respectively, and they have their free ends rounded up and placed at 268 and 269 respectively, being in the path of travel of the can bodies, as they are moving along the guiding rail 174, and being 105 propelled by the star member 175; and the feeler lever 258 is pivoted at 261 and its free end is placed in the path of travel of the can-ends, as they pass through the marker.

The feeler lever 256 controls the feed of 110 can-ends at the stack, while the feeler levers 257 and 258 control the clutch for driving the machine.

A bell crank lever 262 is pivoted on top of the shaft 214 and has one arm 263 connected by means of the rod 264 with the arm 265 of the feeler lever 256, and at the other end said bell crank lever carries a steel strip 266, formed at the point with a knife edge 267, adapted to enter beneath the stack of 120 can-ends just below the lowermost can-end, when the stack is resting upon the upper surface of the separating plate 218, in order to prevent the stack from dropping down upon the supporting gauging tongue 221, 125 when there is no can at 268 on the can body feed disc 173.

The point 268, where the can is located at the time it engages the free end of the lever 256, is determined by the time the 130

- rear end of one of the separating plates 218 has moved out from beneath the stack, and the time the forward beveled end of the other plate 218 has entered beneath said stack. If during this interval of time the point 267 is not withdrawn from beneath the can-end stack by the presence of a can at 268, the lowermost can-end will remain located at an elevation above the reach of 6
- 10 the point 225 of the separating disc and will remain in the stack, on the other hand, if during said interval of time there is a can present at 268, the point 267 will be withdrawn and the stack will then be supported 15 by the edge of the separating plate 218, and when this edge is moved out from underneath the stack, will drop down upon the supporting gauging tongue, and the lowermost can-end will be in a position to become 20 engaged by the separating plate and delivered to the marking mechanism.

The mechanism just described fulfills condition 4 above stated and does not interfere with the working of the machine under the 25 other conditions.

The mechanism controlling the action of the power clutch is the following:

A vertical shaft 253 is mounted at the bottom in the bearing 139, provided upon the 30 bottom plate 6, and in a bearing 270, carried upon a bracket 339, secured to the platform 179; said shaft carrying a hand lever 271, keyed to it above the bearing 270, and an arm 302 keyed near the bottom; said 35 arm being adapted to connect at its free end with a clutch, provided on the driving shaft, furnishing power for running the machine.

Upon the hand lever 271 is mounted a vertical stud 272, carrying a pawl member. 40 The pawl member comprises a sleeve 273, carrying the lower pawl arm 274 and the upper actuating arm 275, which is provided at the free end with a vertical pin 276.

The pawl arm 274 is adapted to engage or 45 disengage a notch 281, formed in a block 282, provided upon the lower surface of the swinging arm 252.

A tension spring 277 tends to keep the pawl lever against the stop 278.

50 When the pawl member is free to enter the notch 281, the swinging lever 252, acting through the pawl, throws the arm 271 together with the lower arm 302 to the right, thus causing the disengagement of the clutch 55 on the driving shaft and stopping the machine.

The pawl arm 274 is controlled by the 60 feeler arms 257 and 258 in such a manner, as to keep it out of engagement with the notch 281, thus permitting the machine to run if there is no can at the position 269, irrespective whether there is a can-end or not at the marker, which are the conditions 4 or 2 respectively stated above; or to keep 65 the same pawl out of engagement with the

said notch, when there is a can-end present at the marker, irrespective whether there is or there is not a can at the position 269, which are conditions 1 or 4 respectively, as stated above. 70

The only time the pawl is free to enter the notch 281 is, when there is a can body present at the position 269 and simultaneously there is no can-end at the marker; this is the condition 3 stated above, and in this case the arm 75 271 is actuated by the swinging lever 252 and the machine is stopped.

The mechanism actuating the pawl member consists of a short arm 280, secured upon the hub of the feeler arm 258 by means of the 80 set screw 279, and of another short arm 283 loosely mounted upon the same hub.

When there is a can-end at the marker, the arm 280, as seen from the drawings, comes in contact with the pin 276, forcing it to the 85 right and, swinging the arm 275 to the right, keeps the pawl arm 274 out of engagement with the notch 281; and when there is no can at the point 269, the arm 284 of the feeler lever 257, acting through the bent link 285 connecting it with the short arm 283, pulls said arm towards the pin 276 and, moving said pin and the arm 275 to the right, moves the pawl arm 274 out of engagement with the 90 notch 281. 95

When there is a can body at 269 and there is no can-end at the marker, both arms 280 and 283 will remain at the left of the pin 276, permitting the spring 277 to pull the pawl arm 274 towards the stop 278, ready to become 100 engaged by the notch 281, when the swinging arm 252 finishes its return stroke, and on the forward stroke of said swinging lever, the arm 271 together with the lower lever 302 (see Figure 4) will be moved towards the 105 right, throwing out the clutch and stopping the machine.

The machine is driven by a motor 61, carrying a silent sprocket wheel 286, connecting by means of a silent chain 287 with a silent 110 sprocket wheel 288, loosely mounted on the main driving shaft 289 of the machine, and carrying a friction clutch drum 290 secured to it. A friction clutch center 291 is keyed to the shaft 289 and carries the operating arms 292 provided with the adjusting screws 293. Said arms are actuated by the shifting cone 294, slidably mounted upon the main driving shaft 289 and provided with the usual shifting lever 295, keyed at one end of a shaft 115 296, which is mounted in the bearing 297, carried on a bracket 298, secured to the base 1 of the machine; and in the bearing 299 provided on the base. An arm 300 is keyed at the other end of the shaft, connecting by means of a link 301 with an arm 302, keyed to the vertical shaft 253 above described. 120

The main driving shaft 289 is mounted in the bearings 303 and 304 provided upon the base of the machine, and carries a friction 125 130

brake 305, which is operated by an arm 306, keyed at one end of a rocking shaft 307, mounted in the bearing 308, and carrying at the other end a segment of a bevel gear 309, 5 engaging a similar segment 310 loosely mounted upon the shaft 296.

An arm 311 is keyed to the shaft 296, and carries at the free end a pin 312, adapted to engage a hole 313, drilled in the segment 10 310, thus locking said segment 310 and said arm 311 together, and causing the automatic application of friction to the friction brake 305, when the friction clutch shifting lever 295 is moved to release the friction clutch, 15 and releases the friction brake 305, when the shifting lever is moved to engage the friction clutch to start the machine.

When the machine is to be turned by hand for adjustment, the pin 312 is withdrawn 20 from engagement with the segment 310, and then, while the friction clutch is out of engagement, the friction brake will also be released, making it easy to turn the machine by hand.

25 The main driving shaft 289 carries at the opposite end of the clutch a gear 314, engaging with another gear 315, carried upon a short shaft 316, mounted at one end in the bearing 317, provided upon the base of the 30 machine; and at the other end resting in a bearing 318, carried by a bracket 319.

A bevel pinion 320 is keyed to the shaft 316, engaging a bevel gear 321, keyed to the central shaft 12 of the machine, imparting 35 motion to it. The tubular shaft 11 is driven at a reduced rate of speed from the central shaft 12 by means of a pinion 322, keyed to said central shaft, engaging a spur gear 323, keyed to a counter shaft 324; while a spur pinion 325, keyed to the counter shaft, 40 engages a spur gear 326, keyed to the tubular shaft 11.

The can-end feed shaft 214 is driven from the counter shaft 324 by the spur gear 327, 45 meshing with a spur gear 328, keyed to said can-end feed shaft 214; while a spur gear 329, keyed to the can-end feed shaft, engages a spur gear 330 on the accelerator shaft 180.

The shaft 180 carries a spur gear 331, 50 engaging at one side a similar gear 332, keyed to the can body feeding shaft 176; and at the other side an idler spur gear 333, mounted upon a counter shaft 334, and engaging a gear 335, secured to the can discharge shaft 65 336.

The ratio of gearing between the several shafts are so chosen, as to cause the can feeding shaft 176 and the accelerator shaft 180 to make one revolution, for each revolution 60 of the turret, and the can-end feed shaft 214 and the can discharge shaft 336 to make two complete revolutions in the same time.

For producing a vacuum inside the vacuum casing 65 there is secured upon the top 65 8 of the base a central stationary circular

chamber 340, which is furnished with a pipe 341, leading to a vacuum tank (not shown). A similar central circular chamber 342 is fitted and secured underneath the circular lower disc 18.

70

The chamber 340 is formed upon the upper wall with a channel 343, smoothly finished; while the chamber 342 is provided on the lower surface with an annular channel 344, fitting smoothly inside the channel 343. A groove 345 is cut in the center of the channel 343, corresponding with a similar groove 346, cut in the channel 344, and a plurality of holes 347 are drilled at the bottom of the channel 343, connecting the groove 345 with the inside of the chamber 340; and a plurality of holes 348 are drilled in the channel 344, connecting the groove 346 with the inside of the chamber 342.

75

The chamber 342 is connected with the several vacuum casings 65 by means of the port holes 349 in said chamber, connecting with port holes 350, provided in the lower disc 18, which, in their turn, connect with vertical port holes 351, passing through the centers of the vertical rods 20, and leading through the ports 373, into the interior of the cylindrical shell 26, as shown in Figure 21.

80

Plug valves 353, furnished with the plugs 354, and carrying the operating handles comprising the outer arms 355 and the inner arms 356, are placed in the port holes 350 on the disc 18.

85

In Figures 24 and 25 one of the valves 100 353 is drawn in sectional plan, showing the port holes 350.

90

In Figure 24 the plug 354 and the operating arms 355 and 356 are shown in the position they occupy, when the vacuum casing 65 is disconnected from the vacuum chamber 342, and is connected with the atmosphere; while in Figure 25 the plug 354 is shown in the position, after it had turned one quarter of a revolution in a left hand direction from the position of Figure 24; the vacuum casing 65 being disconnected from the atmosphere and connected with vacuum chamber 342.

95

The plugs 354 are actuated by pins 357 and 358. The pin 357 is carried upon an arm 359 of a bell crank lever, pivoted at 360 to the top plate 8 of the base; the other arm 361 being held by a light tension spring 362 against a stop 363.

100

An upright shaft 364 is mounted in a bearing 365, provided upon the top plate 8 of the base, and in a bearing 366, carried upon the platform 179; and an arm 367 is secured to said shaft at such an elevation, as to engage the lower end of the can bodies, as they are carried around by the turret, resting upon the lower chucks, as shown in Figures 21 and 22.

105

Another double arm, comprising the upper prong 368 and the lower prong 369, is secured 110 130

at the bottom of the shaft 364 at such an elevation, as to bring said lower prong 369 in alignment with the arm 361.

When a can body shown at 370, comes opposite the curved end of the arm 367, the lower prong 369 comes behind the end of the arm 361, locking said arm and holding it against the stop 363. The pin 357 is then not free to move, and when the turret has advanced, until 10 the arm 355 of the valve plug comes in contact with the pin 357, the pin will turn the plug in a left hand direction, bringing the ports in the plug in the position shown in Figure 25, thus connecting the vacuum casing 65 with the vacuum chamber 342. The valve plug 354 will remain in the same position, keeping the vacuum casing 65 under vacuum, until the can inside the casing is double seamed, when the arm 356 of the 20 valve plug will come in contact with the stationary pin 358, and will be turned for one quarter turn in a right hand direction, turning the valve plug to the position shown in Figure 24, and disconnecting the vacuum casing 65 from the vacuum chamber 342, and connecting it with the atmosphere.

After the arm 355 of the valve plug has been operated by the pin 357, a pin 371, carried upon an arm 372, secured to the lower 30 disc 18, engages the upper prong 368, and swinging said prong from the position shown in full lines in Figure 22, to the position shown in dotted lines, causes the shaft 364 to turn in its bearings, bringing the arm 367 and the lower prong 369 to the position, shown in the dotted lines, where the arm 367 is in a position to become engaged by a can body, while the arm 369 is in a position beyond the end of the arm 361 of the bell crank 35 and the lower prong 369 to the position, shown in the dotted lines, where the arm 367 is in a position to become engaged by a can body, while the arm 369 is in a position beyond the end of the arm 361 of the bell crank 40 lever, permitting the latter to swing out of the way of the arm 355 of the valve plug, without operating it, if there is no can upon the lower chuck.

After a plug valve has passed the pin 357, 45 and a port connection has been established between the vacuum chamber 342 and the inside of the vacuum casing of the spindle, the valve plug remains at rest, keeping the inside of said casing under vacuum, and during this time the double seaming of the can-end takes place; and before the plug valve comes opposite the pin 358, the double seaming is completed, and the arm 356 of the valve plug, coming against the stationary pin 358, is turned for a quarter turn, 50 turning the plug valve from the position shown in Figure 25 to the position shown in Figure 24, when the port hole 350, leading from the vacuum casing of the spindle is connected to the atmosphere, relieving the vacuum inside the casing 65. The vacuum casing is then raised by the cam track 146, and the cylindrical shell 26 is lowered, and the can 55 is ready to be removed from the machine.

65 The mechanism serving for the discharge

of the cans consists of a bar 374, furnished with a central hub 376, whereby it is keyed to the can discharge shaft 336, and is provided at the ends with the pockets 375, which fit the can bodies, and engaging them, propel 70 them along the discharge chute 377, where they are guided by the guide plate 198.

The height of the seaming spindles above the lower chucks 22 may be altered for seaming cans of different heights, by raising or 75 lowering the cylindrical casting 15, which is secured to the top plate 16 by means of the upper nut 378 and lower jam nut 379.

Since the cam tracks 146 and 170 are fastened to the cylindrical casting, the raising 80 or lowering of the same does not destroy the adjustment of the mechanism operating the raising or lowering of the spindles and the action of the knockout rod, the travel of the spindles and of the knockout rod remains the 85 same for all heights of cans.

Before the cylindrical casting 15 is raised or lowered, the set screws, holding the discs 56 and 58 secure upon the tubular shaft 11, are loosened and then the nuts 378 and 379 are 90 so manipulated, as to raise or lower the cylindrical casting and with it the upper part of the turret, together with the spindles; and then the turret is made fast upon the tubular shaft 11, and the weight of the turret is then 95 sustained by the thrust bearing 17, relieving the load from upper plate 16.

The stroke of the cylindrical shell 26 varies with cans of different heights and, when this difference is small, no changes in the swing of the 'rocking lever is required, the difference in height being taken up by the spring 34; while for greater variations the cam lever may have to be changed.

Having thus described our invention, what 105 we claim and desire to secure by Letters Patent is:

1. In a machine of the character described a rotatory circular table adapted to receive and convey can bodies at a low velocity, a plurality of seaming spindles, a turret adapted to support and convey said seaming spindles at a higher velocity, said circular table and said turret rotating in the same direction, and accelerating devices adapted to engage said can bodies while moving at said low velocity and transfer them to the seaming spindles accelerating said low velocity to the higher velocity of the spindles, said accelerating devices comprising a rotary disc interposed between said circular table and said turret arranged to rotate in the opposite direction to that of the circular table and provided with guides, sliding bars mounted in said guides and provided at the ends with means for engaging the can bodies, and a cam track for sliding said bars inside said guide.

2. In a machine of the character described a rotatory circular table adapted to receive and convey can bodies at a low velocity, a plu-

rality of seaming spindles, a turret adapted to support and convey said seaming spindles at a higher velocity, said circular table and said turret rotating in the same direction 5 and accelerating devices adapted to engage said can bodies while moving at said low velocity and transfer them to the seaming spindles accelerating said low velocity to the higher velocity of the spindles, said accelerating devices comprising a rotary disc interposed between said circular table and said turret arranged to rotate in the opposite direction to that of the circular table and provided with guides, sliding bars mounted in 15 said guides and provided at the ends with trueing jaws adapted to engage can bodies, and a cam track for sliding said bars inside said guides.

3. In a machine of the character described 20 a rotary member adapted to receive and convey can bodies at a low velocity, a plurality of seaming spindles, a turret adapted to support and convey said seaming spindles at a higher velocity, said rotary member and said turret 25 rotating in the same direction, and accelerating devices adapted to engage said can bodies while moving at said low velocity and transfer them to the seaming spindles, accelerating said low velocity to the higher velocity of the spindles, said accelerating devices comprising 30 a rotary disc interposed between said rotary member and said turret arranged to rotate in the opposite direction to that of said rotary member and provided with guides, sliding bars mounted in said guides and provided at the ends with means for engaging the can bodies, and means for sliding said bars inside said guides.

4. In a machine of the character described 40 a rotary member adapted to receive and convey can bodies at a low velocity, a plurality of seaming spindles, a turret adapted to support and convey said spindles at a higher velocity, said rotary member and said turret 45 rotating in the same direction and accelerating devices adapted to engage said can bodies while moving at said low velocity and transfer them to the seaming spindles accelerating said low velocity to the higher velocity 50 of the spindles, said accelerating devices comprising a rotary disc interposed between said rotary member and said turret arranged to rotate in the opposite direction to that of said rotary member and provided with a 55 plurality of guides running in different directions and placed at different elevations, sliding bars mounted in each of said guides and provided at the ends with means for engaging the cans, a cam track placed below said sliding bars, and cam rollers mounted on pins of different length secured near the ends of said bars and adapted to engage said cam track.

5. In a machine of the character described 65 a rotatory member adapted to receive and

convey can bodies at a low velocity, a plurality of seaming spindles, a turret adapted to support and convey said spindles along a circular path at a higher velocity, and accelerating devices adapted to engage said can bodies while moving at said low velocity, carry them with an accelerating velocity along a curved path to the circular path of the seaming spindles and then carry them for some distance along said circular path 70 in vertical alignment with said spindles. 75

6. In a machine of the character described a rotary member adapted to receive and convey can bodies, a plurality of seaming spindles, a turret adapted to support and convey said spindles along a circular path, can trueing and centering jaws carried upon said turret in vertical alignment with said spindles, transferring devices furnished with can trueing jaws adapted to engage the can bodies and transfer them from said rotary member to said circular path and carry them a short distance along said path where the said trueing jaws of the turret and the trueing jaws of the transferring devices both 80 engage the can bodies and give them a circular form, and means for bringing down a can-end upon the can body while both trueing jaws travel along said short distance of 85 the circular path of the spindles. 90

7. In a machine of the character described a rotary member adapted to receive and convey filled cans, a plurality of seaming spindles, a turret adapted to support and convey said spindles along a circular path, transferring devices adapted to engage said can bodies, carry them from said rotary member along a curved path and deliver them to said spindles, a can-end track placed above the path of travel of the can bodies from said rotary member to said turret; said track having a gradual incline downward, and vertical pins carried by said transferring devices adapted to engage the can-ends and propel them along the track, keeping them in vertical alignment with said can bodies. 100

8. In a machine of the character described a rotary member adapted to receive and convey can bodies at a low velocity, a plurality of seaming spindles, a turret adapted to support and convey said spindles along a circular path at a higher velocity, can trueing and centering jaws carried upon said turret in vertical alignment with said spindles, can accelerating devices furnished with trueing jaws adapted to engage the can bodies while moving at said low velocity, accelerate said velocity to the higher velocity of the spindles and then carry them for a short distance along said circular path; the trueing jaws of the turret and the trueing jaws of the accelerating devices, engaging the cans from opposite sides to give them a circular form, and means for bringing down a can-end upon the can body while both travel along said dis- 115 120 125 130

tance of the circular path of the spindles.

9. In a machine of the character described a turret mounted upon a vertical shaft, a plurality of lower can supporting chucks secured to said turret at a permanent elevation, automatic means for placing can bodies furnished with can-ends to be seamed upon said chucks, a plurality of seaming spindles slidably mounted in vertical bearings upon said 5 turret in alignment with said lower chucks, upper chucks and seaming rollers carried by said spindles, means for lowering said spindles in order to bring the upper chucks and seaming rollers in the proper relation to the 10 can for double seaming, driving means for carrying the seaming rollers around the can, means for feeding the seaming rollers towards or away from the can while performing the double seaming, and means for raising the seaming spindles above the cans after 15 the double seaming is completed.

10. In a machine of the character described a turret mounted upon a vertical shaft, a plurality of circular platforms 20 adapted to support filled cans secured at the lower end of the turret at a permanent elevation, cylindrical shells slidably fitted around said platforms, vacuum casings slidably mounted in vertical bearings upon said 25 turret above and in alignment with said platforms, seaming mechanism rotatably mounted within the casings and moving vertically together with them, means for lowering the casings in order to lower the seaming 30 mechanism to the operating elevation for double seaming, means for raising the cylindrical shells to meet the bottoms of said casings and to form tight joints with them and with the bottom faces of said platforms, 35 means for creating a vacuum inside the casings, and means for actuating the seaming mechanism to close the cans.

11. In a machine of the character described a turret mounted upon a vertical shaft, can supporting platforms secured by 40 vertical rods to the lower part of said turret, cylindrical shells slidably fitted around said platforms, vacuum casings slidably mounted in vertical bearings upon said turret above 45 and in alignment with said platforms; seaming mechanism rotatably mounted within the casings and moving vertically together with them, rubber packing rings provided upon the bottom of the casings and rubber 50 packing rings provided at the lower part inside the cylindrical shells; said packing rings forming air tight joints between the shells and the casings and between said shells and the platforms, means for raising or lowering 55 said cylindrical shells, and means for lowering or raising said casings.

12. In a machine of the character described a turret mounted upon a vertical shaft, a plurality of circular platforms secured at the lower end of the turret at a per- 60

manent elevation, vacuum casings slidably mounted in vertical bearings upon said turret above and in alignment with said platforms, seaming mechanism rotatably mounted within the casings and moving vertically together with them, cylindrical shells slidably fitted around said platforms, means for lowering the casings in order to lower the seaming mechanism to the operating elevation for double seaming, and means for raising the cylindrical shell to meet the bottom of said casing; said means comprising a lever pivoted at one end to the turret and operatively connecting at the other end to the shell, and a cam arm provided with a cam slot engaging a roller carried upon said lever, and operated by an arm receiving motion from a stationary cam track.

13. In a machine of the character described a rotary member adapted to receive and convey can bodies at a low velocity, a plurality of seaming spindles, a turret adapted to support and convey said spindles along a circular path at a higher velocity, and accelerating devices adapted to engage said can bodies while moving at said low velocity, carry them with an accelerating velocity along a curved path to the circular path of the spindles and then carry them for a short distance along said circular path; said accelerating devices comprising a rotary disc provided with a guide, a bar slidably fitted in said guide and provided at the ends with means for engaging can bodies, a cam track having a symmetrical shape placed below said bar and cam rollers mounted upon said bar, one near each end; the said cam track being so formed as to engage one roller on said bar at a time.

14. In a machine of the character described a turret mounted upon a vertical shaft, vacuum casings slidably mounted in vertical bearings upon said turret, seaming spindles rotatably mounted within the casings and moving vertically together with them, seaming heads secured to said spindles, a pair of seaming rollers for curling the rim of a can-end and the flange of a can body into a seam and another pair of seaming rollers for flattening said seam both carried upon said seaming head, and means for actuating said seaming rollers comprising a single member receiving rotary motion from outside of the vacuum casing and passing in the interior thereof, a driving gear and the said seaming head being secured to said single member, a gear loosely mounted upon said single member, a timing cam controlling the feed of the seaming rollers toward or away from the can keyed to said loosely mounted gear, a pin fixed in the casing a pair of gears fastened together and mounted upon said pin, one of said gears receiving motion from said keyed gear while the other is imparting motion to said loose gear and to said timing cam, and

means operatively connecting said seaming rollers with said timing cam.

15. In a machine of the character described a vacuum casing, a seaming spindle carrying seaming rollers mounted inside said casing, and means for operating said seaming rollers at the proper time from the outside of the casing; said means comprising a single rotary member receiving power from outside 5 of the vacuum casing and passing into the interior thereof; a driving gear and a seaming head carrying the said seaming rollers, both keyed to said rotary member, a gear loosely mounted upon said rotary member, a 10 timing cam controlling the feed of the seaming rollers to and from the center of the can keyed to said loosely mounted gear, and operatively connecting with said seaming rollers, a pair of gears fastened together and 15 mounted upon a pin fixed in the casing, one of said gears receiving motion from said keyed gear while the other is imparting motion to the loosely mounted gear, the teeth of 20 the two sets of gears being cut at different 25 slanting angles.

16. In a machine of the character described a rotary seaming spindle, a seaming head secured to and adapted to rotate in unison with said spindle, seaming rollers mounted upon said seaming head, a timing cam rotatably mounted upon said spindle and operatively connecting with said seaming rollers, gearing connecting said spindle with said timing cam proportioned to give the proper 30 relative speed of the former to that of the latter, a vacuum casing entirely enclosing said seaming head, seaming rollers, timing cam and gearing, means for introducing a can body and a can end inside said vacuum 35 casing, and means for producing a vacuum 40 inside said casing.

17. In a machine of the character described a rotary seaming head keyed upon a spindle, a non-rotatory chuck held centrally below said 45 seaming head, bearings oppositely disposed provided in said seaming head, short shafts mounted in said bearings, seaming arms each provided with central hubs and with sockets at both ends secured at the lower ends of said 50 shafts, a seaming roller for curling the rim of a can-end and the flange of a can body into a seam mounted in a socket at one end of each arm and a seaming roller for flattening the seam mounted at the other end of each arm, 55 operating arms secured at one end to the upper ends of said shafts carrying at the other end a cam roller and a cam having a symmetrical form adapted to engage the cam rollers of both operating arms and actuate 60 them so as to bring first the curling rollers of the seaming arms to bear upon the rim of the can-end from the opposite directions and then moving the curling rollers away from the seam and bring the flattening rollers to 65 bear upon and close the seam.

18. A vacuum double seamer comprising a base, vertical columns mounted upon said base, a top plate supported by said columns, a turret comprising a number of discs secured to a tubular shaft and mounted upon a central shaft resting at one end in a bearing provided on the base and at the other end in a bearing provided in an adjustable cylindrical casting, circular platforms adapted to support can bodies at a permanent elevation and 70 surrounded by sliding cylindrical shells mounted upon the lower disc, vacuum casings carrying seaming spindles and slidably mounted in bearings upon the upper discs of said turret, a driving gear keyed to said central shaft meshing with a gear provided upon a member of each of said seaming spindles to impart rotation to said spindles, means for driving said central shaft, means for rotating said tubular shaft and said turret 75 around said central shaft, means for lowering or raising said vacuum casings, and means for raising or lowering said cylindrical shells. 80

19. In a machine of the character described a circular platform adapted to support a can, a cylindrical shell fitted around said platform and provided with a rubber packing ring, a seaming spindle mounted above said platform, a vacuum casing enclosing said spindle and provided at the bottom with a packing ring, and means for bringing said vacuum casing and said cylindrical shell together to form air tight joints between said cylindrical shell and said casing and between the cylindrical shell and said platform, said 90 means including a swinging lever engaging said shell and a cam lever mounted upon a shaft and provided at the free end with a cam slot engaging a roller carried upon said lever, the portion of said cam slot corresponding with the uppermost position of said lever, being concentric with the center of said shaft. 95

20. In a machine of the character described, a seaming spindle comprising a rotatable outer sleeve, a non-rotatable inner tube, and a non-rotatable knockout rod, a vacuum casing surrounding said spindle and provided at the top with a stuffing box, a gear secured to the outer sleeve above said stuffing box for receiving power from the outside of the casing, a seaming head furnished with seaming rollers secured to said sleeve, a timing cam for feeding the seaming rollers rotatably mounted upon said spindle and driven by means of gears enclosed inside the non-rotatable vacuum casing, and means for actuating said knockout rod. 100 110

21. In a machine of the character described a seaming spindle comprising a rotatable outer sleeve provided with a seaming head carrying seaming mechanism, a vacuum casing surrounding said seaming head and seaming mechanism, a stuffing box provided upon the upper part of said vacuum casing, a gear 115 120 125 130

keyed upon the rotatable outer sleeve above said stuffing box, a non-rotatable sliding head for imparting vertical motion to said seaming spindle and said vacuum casing, provided

- 5 with a ball bearing and mounted at the upper end of said rotatable outer sleeve, a non-rotatable inner tube carrying at the lower end a chuck, and placed inside said outer sleeve extending above and beyond said sleeve and 70
10 secured to said sliding head, and a stuffing box provided at the top of the sliding head to close the joint between the non-rotatable inner tube and the inside of the outer sleeve. 75

22. In a machine of the character described 15
15 scribed a turret mounted upon a vertical shaft, a plurality of circular platforms adapted to support cans secured at the lower part of said turret, seaming spindles slidably mounted upon the upper part of said turret, 20
20 and means for raising and lowering said seaming spindles; said means comprising a non-rotatable sliding head placed upon the upper part of each spindle and furnished with a ball bearing permitting the rotation of 25
25 said spindle and sustaining the weight of the same, arms oppositely disposed provided upon each sliding head, pins carried by said arms, antifriction rollers mounted upon said pins; forked bell crank levers provided with 30
30 cam slots engaging said antifriction rollers pivoted upon the upper part of the turret and a stationary cam track actuating said forked levers.

23. In a machine of the character described 35
35 a turret mounted upon a vertical shaft, a plurality of circular platforms adapted to support can bodies secured at the lower part of said turret, tubular seaming spindles mounted upon the upper part of said turret, non-rotatable inner tubes placed inside said spindles carrying chucks engaging the can ends when said spindles are lowered, knockout rods placed inside said tubes, and devices for lowering said knockout rods when a can-end is 40
40 placed upon the can body and raised when the can is to be discharged; said devices comprising a rack provided with gear teeth secured upon the knockout rod, engaging a gear segment carried upon a rocking shaft supported 45
45 in bearings upon the turret, and actuated by a cam track imparting motion to an arm secured upon said shaft. 50

24. In a machine of the character described 55
55 a plurality of seaming spindles mounted upon a continuously running turret, a rotary member carrying can bodies to be delivered to said spindles, a can-end magazine having a base formed with a circular bore, a can-end track communicating with said bore, vertical 60
60 guide rods for guiding a stack of can-ends mounted upon said base, a short strip secured to said base and having one end projecting inside said bore giving support to the stack at one side, another strip slidably mounted in 65
65 the proximity of the base giving support to

said stack at the other side, a rotary disc, can-end separating plates mounted upon said rotary disc and provided with knife edges adapted to enter between the lowermost can-end in the stack and the one above it and lower one side of said can end, means actuated by the presence of a can body upon said rotary member and adapted to withdraw the end of said sliding strip from under the stack, and propelling pins carried upon said rotary disc adapted to engage the lowered can end, introduce it into said track and carry it for a definite distance along said track. 70
75

25. In a machine of the character described a can-end feeding device for supplying can-ends to can bodies comprising a can-end magazine furnished with a base provided with a circular bore, a stationary projection placed inside said bore for supporting the stack at one side, and a rotating disc supporting the other side, a vertical shaft carrying said rotating disc, can-end separating plates provided with knife edges adapted to enter between the lowermost can end in the stack and the one above it secured to said rotating disc 80
85 partly covering it, leaving uncovered portions forming can-end gauging and stack supporting tongues, means for rotating said discs in order to withdraw the rear end of a separating plate from under the stack letting the stack drop upon said gauging tongue, and in order to introduce the knife edges and the separating plates between the lowermost can end and the rest of the stack, and propelling pins projecting downwards from said rotating disc for removing the lowermost can-end 90
95 from underneath the stack. 100

26. In a machine of the character described a plurality of seaming spindles, means for supplying can bodies to said spindles, a can-end magazine carrying a stack of can-ends, a can-end marking device stationarily mounted, and provided with an operating arm, a vertical separating shaft, a rotary can-end separating device mounted upon said vertical separating shaft and adapted to separate the lowermost can-end in the stack, and deliver it to said marking device, and means for actuating said operating arm; said means comprising a cam secured upon said separating shaft, a swinging arm provided at the end with a cam roller receiving motion from said cam, and carrying a rib, having its upper surface formed into a cam, operatively connecting with said operating arm. 105
110
115

27. In a machine of the character described a continuously revolving turret, a plurality of vertical seaming spindles slidably mounted upon said turret, vacuum casings surrounding said spindles and adapted to slide in unison with them, can supporting platforms rigidly secured upon the turret below said spindles and in alignment with them, cylindrical shells surrounding said platforms, 120
125
130

- devices for placing can bodies with loose can ends upon said platforms, a packing ring secured inside each cylindrical shell, a packing ring provided upon each vacuum casing, 5 means for raising said cylindrical shells bringing the packing rings of the shells in contact with the bottom edges of the stationary can supporting platforms, means for lowering said vacuum casings bringing the packing rings of said casings to seat upon the top edges of the cylindrical shells, and means for creating a vacuum inside said chambers. 10 28. In a machine of the character described a turret, a plurality of movable vacuum casings adapted to enclose cans and furnished with seaming mechanism carried upon said turret, and means for connecting said movable vacuum casings with a stationary vacuum supply; said means comprising a stationary vacuum chamber formed on top with a circular groove, a rotatable vacuum chamber secured to said turret and formed at the bottom with an annular channel fitting inside said groove, a plurality of openings connecting both said vacuum chambers, port holes connecting said rotatable vacuum chamber with said movable vacuum casings, rotary plug valves placed inside said port holes, arms carried upon said plugs, and pins rigidly held and adapted to engage said arms actuating said plug valves. 15 25 30 29. In a machine of the character described a plurality of seaming spindles mounted upon a continuously running turret, devices for delivering can bodies to said spindles, and means for placing a can end upon each of said bodies; said means comprising a can end magazine having a base formed with a circular bore, a can end track provided with 35 40 45 50 55 60 65 70 75 80 85 90 95 100 105 110 115 120 125 130 grooves for guiding can ends secured to said base, and carried above the path of travel of said can bodies, vertical guide rods for guiding a stack of can ends mounted upon said base, a short strip secured to said base and having one end projecting inside said bore, giving support to the stack at one side, a sliding strip mounted in the proximity of the base giving support to said stack at the other side, a shelf provided within said bore below said sliding strip, a rotary disc, can end separating plates mounted upon said rotary disc and provided with knife edges adapted to enter the stack next above the lowermost can end, means for withdrawing the end of the slideable strip from beneath the stack, allowing it to rest upon one of said separating plates, means for withdrawing said separating plate from beneath the stack, allowing it to drop upon said disc, means acting to introduce the knife edge of a second separating plate next above the lowermost can end in the stack, lowering the side of it upon the shelf, means for returning the end of the sliding strip beneath the stack, and means for removing the lowermost can end from the magazine. In testimony whereof we affix our signatures.
